UNITED STATES PATENT OFFICE.

ROBERT FULTON COMSTOCK, OF LOUISVILLE, KENTUCKY, ASSIGNOR TO BESSIRE & COMPANY, OF INDIANAPOLIS, INDIANA, A CORPORATION OF INDIANA.

BATTER PUMP.

Application filed September 26, 1924. Serial No. 740,128.

To all whom it may concern:

Be it known that I, ROBERT FULTON Comstock, a citizen of the United States, residing at Louisville, in the county of Jefferson and State of Kentucky, have invented certain new and useful Improvements in Batter Pumps, of which the following is a specification.

My said invention relates to a batter pump intended primarily for use in making ice cream cones and it is an object of the invention to provide a pump of this character which shall act in a very direct manner so as to distribute batter taken from a reservoir to the molds of the machine with a minimum of contact with other parts of the mechanism. Due to this fact and also to the fact that the parts are operated very accurately it is possible to reduce to a minimum the waste of batter in the mold.

Referring to the accompanying drawings which are made a part hereof and on which similar reference characters indicate similar parts:

25 Figure 1 is a plan of my device partly broken away;

Figure 2 a section on the line 2—2 of Figure 1;

Figure 3 a longitudinal section; and

30 Figure 4 a transverse section on line 4—4 of Figure 3 showing certain parts in the opposite position from that of Figure 2.

In the drawings reference character 10 indicates the base of the machine said base having a conduit 11 underneath leading from a pipe 12 connected to a reservoir of any convenient form for holding the batter to be made into ice cream cones. A plug 13 closes the outer end of said passage and provides means whereby the same may be readily accessible as for cleaning and the like. A plurality of branch passages 14 extend laterally and then upward from the main passage 11. A similar number of passages 15 extend downward through the base, said passages communicating in any desirable or conventional manner with the molds in which are formed the cones for the reception of ice cream. Above the passages referred to a block 16 is slidably mounted on the base said block having at its lower end an oppositely dovetailed projection 17 extending under corresponding overhanging parts on the base 10.

55 For convenience in entering and removing

the block a triangular shim 18 is located between one of said dovetailed parts and one of over-hanging parts on the base. Said shim also serves to compensate for wear between the engaging sides of the block 16 and the base by means of set screws 19 arranged to bear against the outer side of the shim, these set screws being provided with lock nuts 20 for securing them in place. Obviously a series of shims may be provided instead of the single one illustrated without changing the invention.

The block has a series of cylinders 21 corresponding in number to the branch passages 14 and 15 which act respectively as inlet and outlet passages for the cylinders. Preferably the cylinders have linings indicated in section at 22 in Figures 3 and 4 but this is not essential. The contacting surfaces of the block 16 and base 10 are lubricated by means of reservoirs 23 at the ends of the block said reservoirs being provided with wicks 24 leading down to such surfaces.

Within the cylinders are provided pistons 25 attached by means of connecting rods 26 to rockarms 27 on a rock-shaft 28 journaled in bearings on the block 16. An arm 29 near one end of the rockshaft extends upward and has a ball-shaped extremity engaging in a slot in a bent lever 30 pivoted at 31. The movement of the lever in one direction is limited by a set screw 32 provided with a lock nut 33.

A rod 34 is connected to the other arm of the bent lever by a slideable pin-and-slot connection and a screw 35 is mounted in a threaded opening in a boss on the rod said screw being locked in place by a nut 36. Adjustment of the screw serves to vary the stroke of the piston, and therefore the charge of batter in each cylinder.

In the operation of my device the block is reciprocated by any suitable means with a throw moving it from the position illustrated in Figure 3 to a position in which the cylinders are directly above the outlet ports 15. When the cylinders are in the position of Figure 3 batter is drawn into them by the upward movement of the pistons and this batter is forced out through the outlet ports in the other position due to the fact that the pin 30' on the lever 30 which moves with the block reaches the end of the slot in rod 34 before the block has attained the end of its

movement in that direction (i. e., to the right) whereupon the bent lever swings about its pivot 31 thereby rocking the arm 29, the shaft 28, and the arms 27 to force the pistons down in their cylinders as the cylinders assume a position over the outlet ports 15. The batter in the cylinders is ejected with a sudden spurt near the end of the above described movement of the block.

10 After the batter has been ejected the block moves back toward the position of Figure 2, the pistons and their operating connections leaving the positions last described until the end of the bent lever next to pin 30' strikes 15 against the screw 35 whereupon the bent lever is quickly thrown back to the position of Figure 1 thereby rocking the arm 29, shaft 28, and arms 27 to lift the pistons and quickly fill the cylinders with batter where- 20 upon the operation may be repeated.

It will be obvious to those skilled in the art that my device may be changed in various ways without departing from the spirit of the invention and therefore I do not limit 25 myself to the specific embodiment shown in the drawings and described in the specification but only as indicated in the appended claims.

Having thus fully described my said invention what I claim is:

30 1. A batter pump comprising a base, a cylinder block slideable on said base, inlet and outlet passages arranged to communicate with the block at different extremities of its movement, a piston in each cylinder, a shaft journaled on said block, rock arms on said shaft connected to said pistons, a bent lever having rocking connection with an arm on said shaft, a lost motion connection be- 35 tween said bent lever and the fixed frame of the machine whereby the pistons are operated at the extremities of movement of the block, substantially as set forth.

2. A batter pump comprising a base, a cylinder block slideable on said base, inlet and outlet passages arranged to communicate with the block at different extremities of its movement, a piston in each cylinder, a shaft journaled on said block, rock arms on said shaft connected to said pistons, a bent lever having rocking connection with an arm on said shaft, a lost motion connection be- 45 tween said bent lever and the fixed frame of the machine whereby the pistons are operated at the extremities of movement of the block, substantially as set forth.

2. A batter pump comprising a base, a cylinder block slideable on said base, inlet and outlet passages arranged to communicate with the block at different extremities of its movement, a piston in each cylinder, a shaft journaled on said block, rock arms on said shaft connected to said pistons, a bent lever having rocking connection with an arm on said shaft, a lost motion connection be- 50 tween said bent lever and the fixed frame of the machine whereby the pistons are operated at the extremities of movement of the block, and means for adjusting the lost motion connection to vary the stroke of the pistons, substantially as set forth.

3. A batter pump comprising a base having a series of inlet and outlet passages for batter, a cylinder block mounted to reciprocate on said base and having a series of cylinders each adapted to register with one of said inlet and outlet passages alternately, a piston in each cylinder, a piston rod connected to each piston, a rockshaft journaled longitudinally of said cylinder block and relatively long rock arms fixed to said shaft and pivotally connected to said piston rods, and means having movement substantially 60 parallel to said rock shaft for operating the same, substantially as set forth.

In witness whereof, I have hereunto set my hand and seal at Louisville, Kentucky, this 24th day of June, A. D. nineteen hundred and twenty-four.

ROBERT FULTON COMSTOCK. [L. S.]
